FIG. 4

FIG. 2

FIG. 3

FIG. 1

FIG. 5

FIG. 1 is a perspective view of a clamp down, back support, arm and full arm support for a stadium seat shown in my design;

FIG. 2 is a side view of the clamp down, back support, arm and full arm support for a stadium seat illustrated in FIG. 1, the opposite side being a mirror image and having substantially the same appearance;

FIG. 3 is a top plan view of the clamp down, back support, arm and full arm support for a stadium seat;

FIG. 4 is a front view of the clamp down, back support, arm and full arm support for a stadium seat; and

FIG. 5 is a rear view of the clamp down, back support, arm and full arm support for a stadium seat.

I claim:

The ornamental design for a clamp down, back support, arm and slanted arm support for a stadium seat, as shown and described.
